Primary Examiner — Wendy L Arminio*Assistant Examiner* — Maheen Khurshid(74) *Attorney, Agent, or Firm* — Chun-Ming Shih;
LANWAY IPR SERVICES(57) **CLAIM**

The ornamental design for an oral irrigator as shown and described.

DESCRIPTION

FIG. 1 is a front perspective view of an oral irrigator showing the new design;

FIG. 2 is rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the oral irrigator that form no part of the claimed design.

1 Claim, 8 Drawing Sheets(56)
